Jackson IPG PLLC(57) **CLAIM**

The ornamental design for an auxiliary positioning device of pedestal grinder, as shown.

DESCRIPTION

FIG. 1 is a front view of an auxiliary positioning device of pedestal grinder showing my new design;

FIG. 2 is a rear view thereof;

FIG. 3 is a left view thereof;

FIG. 4 is a right view thereof;

FIG. 5 is a top view thereof;

FIG. 6 is a bottom view thereof; and,

FIG. 7 is a perspective view thereof.
